UNITED STATES PATENT OFFICE.

WILLIAM EVANS, OF PHILADELPHIA, PENNSYLVANIA.

MACHINE FOR TREATING HIDES, SKINS, OR LEATHER.

SPECIFICATION forming part of Letters Patent No. 587,717, dated August 10, 1897.

Application filed November 20, 1896. Serial No. 612,912. (No model.)

To all whom it may concern:

Be it known that I, WILLIAM EVANS, a citizen of the United States, residing at the city of Philadelphia, in the county of Philadelphia and State of Pennsylvania, have invented certain new and useful Improvements in Machines for Treating Hides, of which the following is a specification.

My invention has relation to a machine for fleshing, scudding, cleansing,slicking,skiving, unhauling, or laying out hides, skins, or leather and for analogous purposes; and it relates particularly to the construction and arrangement of the drum upon which the material to be treated is mounted, as well as to means for grinding or sharpening the blades of the finishing-cylinder thereof.

The principal objects of my invention are, first, to provide in a machine of the character described a drum upon which the hide or skin is supported, said drum consisting of a core or barrel upon which is secured a series of elastic or yielding bands or strips of material, the middle one of said bands or strips being less flexible, elastic, or yielding than the other bands or strips, whereby the ridge or backbone of a skin may be more readily shaved and the skin also stretched or spread out more completely and uniformly, and, second, to provide in a machine of the character described a finishing roll or cylinder adapted to be brought down upon the hide or skin upon the drum by a treadle or other suitable mechanism, the cylinder being normally held above the drum out of operative position with respect thereto by means of supports suspended from a system of counterpoising-levers, and a grinding-block carried by said supports and adapted to traverse the periphery of the cylinder to sharpen the blades of the same.

My invention, stated in general terms, consists of a machine for treating hides, skins, or leather constructed and arranged in substantially the manner hereinafter described and claimed.

The nature and scope of my invention will be more fully understood from the following description, taken in connection with the ac-

companying drawings, forming part hereof, 50 in which—

Figure 1 is a rear end elevational view, partly sectioned, of a machine embodying main features of my invention. Fig. 2 is a top or plan view thereof. Fig. 3 is a cross-sectional view of the machine. Fig. 4 is a side elevation, partly sectioned, illustrating in detail the swinging support for the working roll and for the grinding-block. Fig. 5 is a vertical section illustrating in detail the construction and arrangement of the grinding mechanism. Fig. 6 is a longitudinal sectional view of the drum, and Figs. 7 and 8 are respectively top and end elevational views of a hide or skin adapted to be worked in a machine of my invention.

Referring to the drawings, *a* represents the standards of the machine, preferably mounted upon a base *a'*. In the standards *a* is supported a shaft *b*, having mounted on the same a drum *B*, upon which the hide or skin *B'* is adapted to be supported when worked by the machine. The drum *B* consists of a shell or core formed or built up preferably in five sections, as illustrated in Fig. 6 of the drawings. The central or middle section *b'* is covered by a tightly-fitting sleeve *b*² of rubber, which is vulcanized or treated so that its surface is comparatively firm or hard. The other sections *b*³ are covered by sleeves *b*⁴ of rubber, the surface of which is comparatively soft and more yielding than the central sleeve *b*².

The sleeves *b*² and *b*⁴ are united to the sections preferably in the following manner: Upon the outer face of each section of the drum *B* is provided a series of double-tapered longitudinal grooves or recesses *b*⁵, in order that the yielding material introduced into the same may become fixed against possible slipping or displacement thereof. On the sections thus grooved is provided first a layer of elastic material of a dough-like consistency or a plastic mass, which is pressed into the grooves or recesses *b*⁵. This elastic material, which by preference is rubber, is baked until hard, and an outer layer of vulcanized rubber is then applied thereon by means of cement

or otherwise. The texture of the outer layer varies, so that preferably the central sleeve b^2 is harder and less elastic than the other sleeves b^4 thereof. The drum B thus formed is peculiarly adapted to support a hide or skin B', known as a "cow" or "bull" hide and having the wrinkled central portion B² terminating in the ridge or backbone B³, which portion B² and ridge B³ are adapted to lie upon the central sleeve b^2 . By reason of its harder and less elastic texture this sleeve b^2 permits of the hide being trimmed or shaved down evenly and smoothly across its entire width and the more elastic sections b^4 permit of the stretching or spreading out laterally of the hide or skin in passage through the machine and during treatment of the same therein. Directly above the drum B is suspended a cutter, fleshing, or working cylinder D, the shaft d of which is journaled in vertically-movable boxes d' , supported by means of the frames or brackets e , arranged at either end of the shaft d , as illustrated in Figs. 2 and 4 of the drawings. The upper end of each bracket e is pivoted, as at e' , to a counterweighted lever e^3 , which is pivotally supported, as at e^4 , in the frame or standards a of the machine.

The lower end of each bracket is secured to one end of a rod f , the other end of which is pivoted to a treadle-arm f' . The treadle-arms f' are each by preference pivoted at one end in an extension or bracket f^2 of the standards a near the base a' , and the free ends of the arms f' are connected by a foot-piece f^3 , upon which the operator presses to depress, through the treadle-arms f' , rods f , and frames e , the shaft d and cylinder D in the direction of or toward the drum B.

Upon the brackets f^2 is pivoted a lever f^4 , one end of each of which bears against the pivotal connection of the rods f with the treadle-arms f' . The other end of each lever f^4 is counterweighted at f^5 . By thus counterweighting the levers e^3 and f^4 the brackets e , and consequently the cylinder D, are normally elevated and balanced in such manner as that the cylinder D can be depressed by the treadle-arms f' without the usual slip or backlash.

The cylinder D is driven directly from a main shaft (not shown) in the following preferred manner: To one end of the shaft d of the said cylinder is keyed or otherwise secured a pulley h . One of the boxes d' is carried at both sides of the machine by arms h' , pivoted, as at h^2 , to a stud h^3 , upon which rotates an idle-pulley h^4 . The free ends of the arms h' carry a stud h^5 , upon which a pulley h^6 revolves. A belt h^7 is passed around a driving-pulley (not shown) and then under the pulley h^6 , over the pulley h^4 , and under the pulley h , substantially as illustrated in Figs. 1 and 3.

It will be apparent from the above descrip-

tion that any movement up or down of the shaft d and the pulley h will cause a reverse movement down or up of the pulley h^6 , and that therefore a normal tension of the belt h^7 is secured, irrespective of the movement of the shaft d , pulley h , and cylinder D.

The brackets e are connected together by the cross-rods m , upon which a carriage m' is mounted and adapted to be slid by means of the handles m^2 to thereby traverse the length of the cylinder D above the periphery thereof, as illustrated in Figs. 3 and 5. On the carriage m' is arranged a vertically-movable slide m^3 , carrying a block m^4 of emery or other suitable grinding material. The slide m^3 and block m^4 are fed toward or away from the blades of the cylinder D by means of the threaded bolt m^5 , operated by the crank or handle m^6 , supported by an extension or bracket m^7 on the carriage m' , as shown in Fig. 5. By thus mounting the carriage m' and the grinding-block m^4 upon the cross-rods m the grinding mechanism is always in fixed relationship with respect to the cylinder D, and any movement up or down of said cylinder is imparted by the brackets e and cross-rods m to the carriage m' and the block m^4 . Hence no matter what the position of the cylinder be with respect to the drum B its blades may be sharpened and trued by the grinding mechanism hereinbefore explained.

Having thus described the nature and objects of my invention, what I claim as new, and desire to secure by Letters Patent, is—

1. In a machine of the character described, a drum upon which the hide, skin or leather is adapted to be supported and consisting of a cylindrical core or barrel provided with grooves or recesses, a covering of elastic or yielding material of equal thickness throughout applied thereto but the central portion of said applied covering being of a less elastic nature than the end portions thereof, substantially as and for the purposes described.

2. In a machine of the character described, a sectional drum provided with double tapered grooves or recesses, a yielding material or substance applied thereto, and one of said sections being of greater firmness or rigidity than the other sections of said drum, substantially as and for the purposes described.

3. In a machine of the character described, a working roll or cylinder, brackets supporting said cylinder, counterpoising-levers from which said brackets are suspended, cross-rods connecting said brackets and a grinding mechanism supported on and adapted to slide over said rods and maintained in fixed relationship with respect to said cylinder, substantially as and for the purposes described.

4. In a machine of the character described,

two counterweighted arms, a bracket suspended from each arm, a cylinder having its bearings in said brackets, cross-rods connecting said brackets, a carriage supported on and adapted to slide over said cross-rods, a slide vertically movable with respect to the carriage, a grinding-block carried by said slide and means for moving said slide and block in the carriage toward or away from

the periphery of said cylinder, substantially as and for the purposes described.

In testimony whereof I have hereunto set my signature in the presence of two subscribing witnesses.

WILLIAM EVANS.
